UNITED STATES PATENT OFFICE.

JOHN T. BOOTES, OF CEBU, PHILIPPINE ISLANDS.

CYLINDER HEAD FOR ALL TYPES OF WATER-COOLED INTERNAL-COMBUSTION ENGINES.

Application filed June 24, 1926. Serial No. 118,231.

My invention relates to improvement in water cooled cylinder heads for internal combustion engines in which the head is fabricated in two or more sections in such a manner that the lower section is held in position by the upper, no bolts passing through the lower section, due allowance being made for expansion.

The object of my improvement is to provide for readily removing the deposits which collect in the head, thereby preventing overheating and cracking of the cylinder head. This is done by removing the upper section, the lower section then being accessible for removing such deposits as may have collected.

The advantages of the improved head are readily seen. The deposits from minerals in water form an insulation thus preventing the water from coming in contact with the surface of the metal, resulting in overheating and cracking of the cylinder head. The life of this improved head, regularly cleaned, is indefinite, while the life of the head ordinarily used is only about six months; this particularly true of the marine type of engine where sea water is used for cooling.

In the drawings wherein like reference characters denote corresponding parts throughout the several views:

Fig. 1 is a cross section of an assembled head; Fig. 2 is a bottom view of upper section of head showing cylinder head bolt openings and circulating water spaces; Fig. 3 is a cross section of Fig. 2; Fig. 4 is a bottom view of lower section of the improved part of cylinder head and Fig. 5 is a cross section of Fig. 4.

A cylinder head, in accordance with this invention, comprises an outer and an inner section referred to generally by the reference characters 1, 2 respectively.

The section 1 includes a body portion 10, in the form of an annulus, having flush with its rear face an outwardly directed annular flange 11. The inner face of the body portion 10 is formed with an annular flange 12, and also with spaced bosses which extend from the flange 12 to an inwardly extending annular flange 14. The bosses are indicated at 15. The flange 12 is of greater thickness than the flange 14. The flange 12 has its outer face flush with the rear face of the body portion 10, and the flange 14 has its outer face flush with the forward face of the body portion 10. Extending through the

flanges 12, 14 and bosses 15 are bolt openings 5, through which are adapted to extend bolts, not shown, for fixedly securing the section 1 to the body of the cylinder.

The section 1 further includes a collar 16, which is suspended within the body portion 10 at the rear thereof, as well as being eccentrically disposed with respect to the inner face of said body portion. The collar 16, at 65 that end thereof, adjacent the rear face of the body portion 10, is formed with an outwardly extending annular flange 17. Formed integral with the flanges 14 and 17 is a wall-forming member 18 which is of 70 circular cross section. The member 18 extends rearwardly from the flange 14, and is of flaring contour and with the flare gradually increasing from one side towards the other side thereof. The rear face of the 75 flange 12 is rabbeted as at 19. The forward end of the collar 16 is provided with sockets 20 having threaded walls.

The body portion 10, in connection with the flanges 14 and 17, collar 16 and member 80 18 provides a water space 21 which is open at its rear. The rear end of the water space 21 is adapted to be closed by the section 2 and which will be hereinafter referred to. The flange 12, between the bosses 15, is provided with openings 22 for circulating water through the water space 21, and said openings 22 are adapted to communicate with the water jacket of the cylinder, not shown.

The section 2 consists of a disk 23, formed 90 eccentrically thereof, with an opening 24 having a tapered wall, which is rounded, and formed integral with the forward face of the disk 23, is a collar 25 having the wall thereof forming a continuation of the wall of the 95 opening 24. Formed integral with the marginal portion of the disk 23, as well as projecting laterally from the outer edge of the disk 23, is an annular rib 26, having a rounded inner edge 27 and a squared outer 100 edge 28. The rib 26 projects an appropriate distance from the outer edge of the disk 23. The outer edge of the disk 23 is rabbeted as at 29, which provides a peripheral shoulder 105 30, positioned in proximity to the lower face of the rib 26. The shoulder 30, in cross section, extends in a plane parallel to the plane of the rear face of the rib 26.

The rib 26 is adapted to seat in the rabbet 19 formed in the rear face of the section 1, 110 and the disk 23 extends rearwardly from the rear face of the section 1. The collar 25

when the rib 26, is seated in the rabbet 19, extends into the collar 16 and the forward edge of the collar 25 is flush with the forward edge of the collar 16. When the collar 25 is positioned in the collar 16, the rear edge of the collar 16 abuts against the forward face of the disk 23. When the collar 25 is positioned in the collar 16 and the rib 26 seated in the rabbet 19, the rear end of 10 the water space 21 is closed by the section 2. The disk 23, when the section 2 is mounted in position relative to the section 1, extends into the engine cylinder, not shown. The shoulder 30 is adapted to abut against the 15 annular shoulder formed on the wall of the engine cylinder not shown.

Forming a part of the cylinder head, in accordance with this invention, is a hot ball formed of an outer section 3 and an inner section 4. The inner section 4 is of tubular contour, extends through the collar 25 and disk 23, and is provided near its forward end with an outwardly extending annular flange 31, which seats on the forward edge of the collar 25. The section 3 at its inner end, is formed with a laterally extending annular flange 32, which seats on the forward edge of the collar 16 and also upon the flange 17. The inner end of the section 3 is stepped or 30 rabbeted, as at 33, for the purpose of overlapping the flange 31 and the forward edge of the section 4, and for binding the section 4 against the forward edge of the collar 25, when the section 3 is fixedly secured to the collar 16. The section 3 of the hot wall is detachably secured to the collar 16 by holdfast devices 9 which extend through the flange 32 and engage the threaded walls of the socket 20.

40 A packing 7 is interposed between the sections 1 and 2, and a packing 8 is interposed between the sections of the hot ball and the collars 16 and 25.

When the cylinder head is mounted in position with respect to the cylinder body, the section 1 is positioned against the forward end of said body and the forward face of the rib 26. The bolts which extend through the openings 5 secures the section 1 to the 50 cylinder and which in turn clamps the section 2 thereagainst. By removing the bolts, which secures the section 1 to the cylinder, the section 1 can be removed from the section 2 and the walls of the water space 21.

55 The hot ball can be disconnected from the cylinder head without disconnecting the sections thereof.

What I claim is:

60 1. A cylinder head comprising an outer and an inner section, the latter seating in and extending rearwardly from the former at the rear thereof, said outer section consisting of a body portion in the form of an an-

65 nulus having an inwardly extending annular flange at the front and rear thereof and further having suspended therein, at the rear thereof, an eccentrically disposed collar connected with the forward flange by a flaring wall forming member of circular cross section, said body portion, member, collar and flanges forming a water space open at its rear, said inner section closing the rear end of said water space and consisting of a circular disk having an eccentrically disposed opening and a forwardly directed collar registering with said opening and extending into the collar of the outer section, said outer section provided with means for the passage of securing bolts therefor for clamping the inner section in position, and a hot ball detachably connected to the collar of the outer section and extending through the collar of the inner section, and said rear flange provided with openings communicating with said water space. 80

2. A cylinder head formed of an outer and an inner section, the latter seating in and extending rearwardly from the former at the rear thereof and free of direct connection with said outer section, said outer section formed with means to provide a water space closed by said inner sections, said means including an eccentrically disposed collar, said inner section formed with an eccentrically disposed opening and an eccentrically disposed collar extending into the collar of the outer section, and a hot ball detachably secured against the forward edges of said collars and extending through the collar of said inner section, said outer section having its rear provided with openings communicating with said water space. 85

3. A cylinder head formed of an outer section provided with means to form a water space open at its rear and with the rear portion of the inner wall of said space formed of an eccentrically disposed collar, an inner section extended rearwardly from the outer section and including an extended rib seating in the rear of said outer section, said inner section providing means for closing the rear of said water space and including an eccentrically disposed opening and a collar registering with the opening and extending into the collar formed on the inner wall of 110 said water space, and a hot ball seating against the forward end of said collars, detachably connected to the collar on said inner wall and further extending through the collar of the inner section, said outer section 115 having its rear provided with openings communicating with said water space. 100

In testimony whereof, I affix my signature hereto.

JOHN T. BOOTES.
